UNITED STATES PATENT OFFICE.

JOSEPH STOSINSKI AND HENRY KUBIAK, OF PHILADELPHIA, PENNSYLVANIA.

TABLE.

1,182,328.

Specification of Letters Patent.

Patented May 9, 1916.

Application filed August 16, 1915. Serial No. 45,774.

To all whom it may concern:

Be it known that we, JOSEPH STOSINSKI and HENRY KUBIAK, a citizen of the United States and a subject of the Czar of Russia, respectively, residing at Philadelphia, in the county of Philadelphia and State of Pennsylvania, have invented certain new and useful Improvements in Tables, of which the following is a specification.

Our invention relates to improvements in tables, and more particularly to an improved self leveling table in which weighted levers are employed to maintain the table in a horizontal position regardless of the angle of the pedestal supporting the table.

A further object is to provide a table having a central thrust bearing on the pedestal supporting the same having improved means for causing the table to maintain a horizontal position regardless of the position of the pedestal, and provide an arrangement of springs yieldingly securing the table on the pedestal, but allowing the same the necessary movements.

With these and other objects in view, the invention consists in certain novel features of construction and combinations and arrangements of parts as will be more fully hereinafter described and pointed out in the claims.

In the accompanying drawings: Figure 1 is a view in side elevation illustrating our improvements, one of the springs being omitted for purposes of clearness. Fig. 2 is an inverted sectional plan view, the section being taken on the line 2—2 of Fig. 1, and the springs are omitted for purposes of clearness. Fig. 3 is an enlarged detail view in section on the line 3—3 of Fig. 2, and Fig. 4 is a similar view on the line 4—4 of Fig. 2.

1 represents a pedestal, and 2 the table which is made with a central bearing 3 to receive a conical thrust journal 4 and support the table at its center. The table 2 is provided on its under face with four eyes 5, and coiled springs 6 connect the eyes 5 with similar eyes 7 on the pedestal 1, thereby elastically holding the table on the pedestal, yet allowing the same a certain amount of movement in order to accommodate itself with the movement of a ship, and we would have it understood that the springs are so located that they do not interfere in any way with the ordinary movements of the several parts hereinafter described.

Metal brackets 8 and 9 are secured to pedestal 1, and these brackets support worm shafts 10 at right angles to each other. The worm shafts are provided on their ends with beveled pinions 11, which mesh with segments 12 having pivotal mounting on the brackets 8 and 9 respectively. Depending levers 13 are fixed to move with the segments 12, and these levers 13 at their lower ends are provided with weights 14, and the weights compel the levers to maintain a perpendicular regardless of the movement of the ship, and the movement of the levers imparts rotary movement to the worm shafts as will be hereinafter described. The levers 13 are made in two parts 13^a and 13^b, connected by hinges 13^c. These hinges allow the weighted ends of the levers to swing outwardly in one direction, so that when one lever is swinging in its normal path to move the table, the lower end of the other lever can swing on its hinge, and relieve any strain upon the segment and its coöperating parts. This is shown in Fig. 1.

On the shafts 10, worms 15 are secured, and mesh with worm segments 16. The segments 16 are fixed to shafts 17, and the latter are supported in bearings 18 on the under face of the table. The shafts 17 are rendered sufficiently flexible to compensate for varying positions of the table by constructing said shafts of two sections connected by universal joints 17^a. The outer ends of the shafts 17 are fixed to rods 19 and the rods 19 operate as double cranks, and are pivotally connected by links 20 with brackets 21 on the table. The arrangement of rods 19 and links 20 permit a certain amount of flexibility between the shaft 17 and the table, and compensate for various angles which the pedestal may assume. Furthermore, the transmission of motion from the gear segments to the table is through the medium of the several links 20, and the springs 6 and thrust bearing 3 compel the table to move easily and with a certain amount of cushion in all directions, overcoming sudden jars which would of course be objectionable.

Various slight changes might be made in the general form and arrangement of parts described without departing from our invention, and hence we do not limit ourselves to the precise details set forth, but consider ourselves at liberty to make such changes and alterations as fairly fall within the spirit and scope of the appended claims.

Having thus described our invention, what we claim as new and desire to secure by Letters Patent is:

1. A device of the character described, comprising a pedestal, a table movably supported on the pedestal, springs connecting the table with the pedestal, pivoted levers supported on the pedestal, shafts mounted on the pedestal, means for transmitting a turning movement to the shafts when the levers are pivoted, and means operated by the shafts to move the table at an angle to the pedestal when the lever is moved, substantially as described.
2. A device of the character described, comprising a pedestal, a table having a thrust bearing on the pedestal, springs connecting the table with the pedestal, pivoted levers supported on the pedestal, segments secured to move with the pivoted ends of the levers, weights on the lower ends of the levers, worm shafts supported on the pedestal, pinions on the worm shafts meshing with the segments, shafts supported on the bottom of the table, worm segments secured to the last-mentioned shafts and meshing with worms on the worm shafts, rods secured between their ends to said last-mentioned shafts, and links pivotally connecting the ends of said rods with the bottom of the table, substantially as described.
3. A device of the character described, comprising a pedestal, a table having a thrust bearing on the pedestal, springs connecting the table with the pedestal, pivoted levers supported on the pedestal, segments secured to move with the pivoted ends of the levers, weights on the lower ends of the levers, worm shafts supported on the pedestal, pinions on the worm shafts meshing with the segments, shafts supported on the bottom of the table, worm segments secured to the last-mentioned shafts and meshing with worms on the worm shafts, and means

connecting the last-mentioned shafts with the table, substantially as described.

4. A device of the character described, comprising a pedestal, a table having a thrust bearing on the pedestal, springs connecting the table with the pedestal, pivoted levers supported on the pedestal, segments secured to move with the pivoted ends of the levers, weights on the lower ends of the levers, worm shafts supported on the pedestal, pinions on the worm shafts meshing with the segments, shafts supported on the bottom of the table, worm segments secured to the last-mentioned shafts and meshing with worms on the worm shafts, rods secured between their ends to said last-mentioned shafts, and links pivotally connecting the ends of said rods with the bottom of the table, substantially as described.

5. A device of the character described, comprising a pedestal, a table having a thrust bearing on the pedestal, springs connecting the table with the pedestal, levers pivotally supported at their upper ends on the pedestal, said levers comprising two members hinged to swing in one direction only and having weights at their lower ends, and means operated by the levers for moving the table at an angle to the pedestal, substantially as described.

In testimony whereof we have signed our names to this specification in the presence of two subscribing witnesses.

JOSEPH STOSINSKI.
HENRY KUBIAK.
